UNITED STATES PATENT OFFICE.

FRED F. RICKER, OF PHILADELPHIA, PENNSYLVANIA, ASSIGNOR TO
BROMLEY BROTHERS, (LIMITED,) OF SAME PLACE.

DESIGN FOR A CARPET.

SPECIFICATION forming part of Design No. 14,628, dated February 5, 1884.

Application filed January 2, 1884. Term of patent 3½ years.

To all whom it may concern:

Be it known that I, FRED F. RICKER, a citizen of the United States, and a resident of Philadelphia, Pennsylvania, have invented or 5 produced a new and original Design for a Carpet-Pattern, of which the following is a specification.

My design is fully shown in the accompanying drawing, and comprises the figures A, B, 10 D, E, F, G, H, and I. The figures A have central ornaments, *a*, and floral ornaments *b*. The figures B, D, E, and F are mainly of a floral character, comprising stems, leaves, and sprays. The figures G are square and have internal or 15 namentation of the character shown, and the figures H are composed partly of geometrical

figures and partly of leaves and sprays. The figure I consists of leaves, and is arranged in a space bounded by the other figures of the pattern, this space having a background or- 20 namented with squares composed of spots.

I claim—

The design for a carpet-pattern, said design comprising the figures A, B, D, E, F, G, H, and I, all substantially as described and shown. 25

In testimony whereof I have signed my name to this specification in the presence of two sub-
scribing witnesses.

FRED F. RICKER.
